DESIGN FOR A COMBINED STOVE TOP PLATE AND HOT-WATER COIL

Albert B. Trencavel, New York, N. Y.

Application February 24, 1939, Serial No. 83,179

Term of patent 14 years

To all whom it may concern:

Be it known that I, Albert B. Trencavel, a citizen of the United States and a resident of the city of New York, in the county of New York and State of New York, have invented a new, original, and ornamental Design for a Combined Stove Top Plate and Hot-Water Coil, of which the following is a specification, reference being had to the accompanying drawing, constituting a part thereof.

Fig. 1 is a top plan view of a combined stove top plate and hot-water coil showing my new design.

Fig. 2 is a bottom plan view thereof.

I claim:

The ornamental design for a combined stove top plate and hot-water coil, substantially as shown.

ALBERT B. TRENCABEL.
